A. SHOULDERS

SANITARY CHICKEN ROOST

Filed June 24, 1921

The Shurets,
Inventor,

By his Attorney, Hugh S. Wagner,

UNITED STATES PATENT OFFICE.

ABE SHOUTS, OF ST. LOUIS, MISSOURI.

SANITARY CHICKEN ROOST.

Application filed June 24, 1921. Serial No. 480,029.

To all whom it may concern:

Be it known that I, ABE SHOUTS, a citizen of the United States, residing at the city of St. Louis, in the State of Missouri, have invented certain new and useful Improvements in Sanitary Chicken Roosts, of which the following is a specification.

This invention is to prevent lice from crawling to and upon poultry roosts, and provides for the destruction with insecticide of any lice that approach the roost.

In the accompanying drawings forming part of this specification, in which like numbers of reference denote like parts wherever they occur,

Figure 1 is a perspective view of this holder for fowl-roosts;

Figure 2 is a sectional view through the upper part thereof; and

Figure 3 is a similar sectional view of a slightly modified form.

A casting 1 contains counter-sunk screw-holes 2 for attaching the same to a wall or post or other suitable support.

In the same casting 1 is formed a wedge-shaped tapering groove 3, adapted to receive and hold the wedge-shaped and tapering tongue 4 on casting 5.

Within casting 5 is formed a cup or receptacle 6, intended and adapted to contain insecticide, preferably in liquid form. The central stud 7 projects upwardly from the bottom of the said cup 6 and has a stud 8 (as shown in Figure 3), formed thereon, or is provided with an internal bore 9, or the like, adapted to receive and hold the pin 10, which will preferably be sweated therein.

The edge 11 of stud 7 in Figures 1 and 2 contains notches 12 and similar notches 40 are formed in the shoulders 13 in that form of stud 7 shown in Figure 3.

Ridges or projections 14 and 15 formed on the edges 16 and 17 surrounding the holes 18 and 19 in casting 20, are adapted to seat in notches 12 and thereby to prevent the rotation of the castings 20, which are the roost-holders proper and contain counter-

sunk screw-holes 21, by which the roosts (not shown in the drawings) are attached to the holders 20.

Each holder or casting 20 is provided with a plurality of holes 18 and 19, arranged at different angles, whereby it is possible to arrange the roost-holder 20 either at an oblique pitch, as shown in Figure 2, or horizontally as shown in Figure 3.

The tongue 4 is not only wedge-shaped in horizontal cross-section, but, also, tapers downwardly, the groove 3 being made to fit both aspects of this shape.

It will be observed that member 20 is loosely supported on member 5, and that member 5 is loosely supported by member 1. This makes it possible easily to disassemble all the parts to cleanse them thoroughly. It also facilitates the cleansing of the roosts (not shown in the drawings), because a detachable roost is much easier to cleanse than one that is permanently nailed or otherwise fastened in a poultry-roosting house.

Having thus described this invention, I hereby reserve the benefit of all changes in form, arrangement, order, or use of parts, as it is evident that many minor changes may be made therein without departing from the spirit of this invention or the scope of the following claim.

I claim:

In a device of the character described, the combination of a fixed member and detachable members supported thereby, one of the said detachable members containing an insecticide cup, and a stud projecting therefrom, and the other detachable member containing a plurality of sockets, the said sockets being adapted to seat on the said stud, and the said sockets being arranged at different angles.

In testimony whereof I hereunto affix my signature.

ABE SHOUTS.
